(57) **CLAIM**

The ornamental design for finger guard for a T-square, as shown and described.

DESCRIPTION

FIG. 1 is a top perspective view of the present finger guard; FIG. 2 is an enlarged top perspective view of the finger guard of FIG. 1;

FIG. 3 is a front view of the finger guard of FIG. 1;

FIG. 4 is a left side view of the finger guard of FIG. 1;

FIG. 5 is a right side view of same;

FIG. 6 is a top view of the finger guard of FIG. 1; and,

FIG. 7 is a bottom view of same.

The broken lines are provided for environment purposes and do not constitute part of the invention claimed in the embodiment of FIG. 1.
